(57) **CLAIM**

The ornamental design for an infant car seat, as shown and described.

DESCRIPTION

FIG. 1 is a perspective view of an infant car seat in accordance with an embodiment of our new design;

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a left side view of FIG. 1; and,

FIG. 7 is a view showing the infant car seat shown in FIG. 1 in use.

The right side view is a mirror image of the left side view. The broken lines shown in FIG. 7 show environmental structures of the infant car seat and form no part of the claimed design.
